UNITED STATES PATENT OFFICE.

FREDERIC L. BISHOP, OF PITTSBURGH, PENNSYLVANIA.

ELECTRIC HEATING APPARATUS.

1,321,504.

Specification of Letters Patent. Patented Nov. 11, 1919.

Application filed March 16, 1916. Serial No. 84,664.

To all whom it may concern:

Be it known that I, FREDERIC L. BISHOP, a citizen of the United States, residing at Pittsburgh, in the county of Allegheny and State of Pennsylvania, have invented certain new and useful Improvements in Electric Heating Apparatus, of which the following is a full, clear, and exact description, reference being had to the accompanying drawings, forming part of this specification, in which—

Figure 1 is a vertical section showing one form of apparatus embodying my invention.

Fig. 2 is a section, on the line II—II, of Fig. 1.

Fig. 3 is a wiring diagram showing coils, circuits, and one form of current regulator.

Fig. 4 is a detail view showing a part of the current regulator.

Fig. 5 is a vertical section illustrating a quenching tank which may be employed, and

Fig. 6 is a view similar to Fig. 1, but showing the heater adapted for another purpose.

My invention has relation to electric heating apparatus, which has been more particularly designed for use for the purpose of treating metal, particularly iron and steel, for the purpose of altering its molecular structure, as described and claimed in my copending applications, Serial No. 750,844, filed February 26, 1913, and Serial No. 809,831, filed January 2, 1914, the present application being, in part, a division of said application Serial No. 809,831.

The present invention has particular reference to electric heating means of novel character which is adapted to utilize the heating action produced by the action of the magnetic field of an alternating electric current.

My invention provides heating apparatus of this character which is not only adapted to the treatment of metal placed within its magnetic field, but may also be used for heating other substances.

I will first describe my invention with particular relation to the heat treatment of metal.

Referring to the accompanying drawings, the numeral 2 designates a suitable case or closure, preferably constructed of heat insulating material, and within which the

metal objects indicated at A and B are designed to be placed while being subjected to the novel treatment. The apparatus shown in Figs. 1 and 2 is designed for the treatment of two pieces of metal simultaneously. For this purpose I provide within the casing or closure 2, two hollow coils 3, placed side by side. These coils have within them a lining 4 of non-conducting material such as clay, terra cotta or mica. I also preferably place within the linings 4 a metal lining 5 which serves to protect the linings 4 from direct contact with the metal. This inner shell 5 may be in the form of a closed cylinder, in which induced eddy currents will circulate, as shown at the left hand side of Fig. 2; or it may be divided into segments, as shown at the right hand side of Fig. 2, to prevent the circulation of induced electric currents therein. The magnetic circuits of the coils or windings 3 is completed through the metallic head block 6, which is preferably laminated as shown; and when the apparatus is in use it is placed over a suitable pit or other support containing a base block 7 of magnetic material. The lower ends of the hollow coils are arranged to be closed by means of doors 8 having removable pivots 9 and arranged to be held closed by means of suitable latch devices 10. Each of the coils or windings 3 is preferably composed of a number of separate coils 3^a, as shown in Fig. 3. These coils are arranged to receive current from an alternating generator 11 through a current regulating switch 12 by means of which the coils may be connected in various ways. The terminals of the several coils 3^a are connected to the series of relatively fixed contact fingers 13 which are arranged to be engaged by a series of movable contacts 14. This movable contact member is shown as having five positions with respect to the contacts 13, namely, the open circuit position in which the parts are shown in Fig. 3, and the positions indicated by the several dotted lines a, a, b, b, c, c, d, d; the position d, d being an open circuit position. Without tracing out the circuits of the coils in detail in the several positions of the current regulating switch, it will be readily seen that in the position a, a all the coils will be connected in parallel; that in the position b, b the two upper coils will be connected in series with each

95

110

other and in parallel with the two lower coils; and that in the position *c*, *c* all four coils will be connected in series.

It is desirable to make use of the changes 5 in the magnetic properties of the metal being treated to automatically control the heating operation and to cut off the current when the desired treatment is complete. For this purpose it is necessary to provide 10 the member of the current regulating switch which carries the movable contacts 13 with an actuating device capable of effecting a step by step movement of said member as the current in the circuit of the coils 3^a changes. This may be accomplished in various ways. In the current regulator shown 15 in Figs. 3 and 4, the member carrying the contacts 14 is arranged to be moved laterally with respect to the contacts 13 and is 20 connected to a movable plunger 15. This plunger at its opposite end extends within the closed receptacle 16 designed to be partially filled with oil or other suitable liquid, and carries therein a piston composed of a 25 plurality of separated plates 17. These plates are provided with perforations 18 adapted to permit of a relatively slow circulation of the oil therethrough. The piston is provided with a series of teeth or 30 notches 19 for engagement with a pivoted dog 20 which forms the armature of an electromagnet 21 which is connected in series in the supply circuit for the coils. The armature dog 20 has a lever arm 22 connected 35 thereto and carries an adjustable counterweight 23. The armature dog 20 is arranged to hold the rod or plunger 15 against the action of a counterweight 24 connected thereto.

40 The operation is as follows:

The metal objects A and B to be treated are first set upon the doors 8, which have been detached from the apparatus by the removal of the pivots 9. The casing or closure 45 2 is (by a crane or any other suitable means) brought over the said metal objects and dropped over them so that they are inclosed within the coils or windings in the manner shown in Figs. 1 and 2. The pins 9 are then inserted and the doors are 50 secured by the latches 10. The entire apparatus is then moved over the pit or other support shown in Fig. 1 and placed in such position thereon that the base block 7 of 55 magnetic material is directly below the pieces A and B. The necessary circuit connections for the coils are then established and the current regulating switch is manually moved to the position indicated 60 by the dotted line *a*, *a*. The several coils 3^a of each winding remain connected in parallel until the metal is preferably heated to a temperature near the recalcitrance point of the metal. At this time the changes in 65 the magnetic properties of the metal tend

to allow a material increase in the flow of current through the coils. This increased flow of current energizes the magnet 21 to an extent where it will overcome the action of the counterweight 23 and will attract the 70 armature dog 20, thus releasing said dog from its engagement with the rod or plunger 15. The counterweight 24 now acts to remove said rod or plunger against the action of the oil in the receptacle 16 and a total 75 distance substantially equal to the distance between adjacent notches or teeth of said plunger where it is stopped by the resistance of the oil. This connects the coils 3^a in series-parallel, thus increasing their 80 resistance and cutting down the flow of current proportionately to such increase. This weakens the magnet 21, and the armature dog now drops into engagement with the next tooth or notch. 85

As the temperature of the pieces A and B continues to increase, a further increase in current takes place in the circuit of the said coils, resulting in another step movement of the regulator and so on until the 90 proper treatment has been given to the metal when the circuit is opened by the regulator.

In this manner the proper limit of temperature is not only automatically indicated, but the current is automatically shut off and 95 heating beyond such temperature is prevented. It will be understood, however, that for certain purposes the predetermined temperature may be other than that above described. That is to say, the device may 100 be so adjusted that it will shut off the current before the recalcitrance point is reached, if this should be desirable in any particular case. In some instances it is desirable to shut off the current when a temperature 105 just below the recalcitrance point is reached. Inasmuch as the current flow has commenced to increase materially at some degrees below the recalcitrance point, the regulating device can be readily set so as to cut 110 off the current flow after the current increase commences and before its maximum flow is reached. In some cases also it may be desirable to carry the heating beyond the recalcitrance point and beyond the temperature 115 at which the metal loses its magnetic properties. In such cases, the regulating device is simply so adjusted that it will not trip at the recalcitrance point but the current will remain on until shut off by other 120 means. In such case the coils 3^a may be used as resistance units and the material heated directly from said coils, instead of by the action of the currents induced in the metal. 125

After the treatment is completed, the apparatus may be removed from the pit or other support and carried over a quenching tank containing the quenching liquid. The bottom doors 8 can then be released and the 130

pieces A and B dropped, while still in the vertical position, directly into the tank. This is a feature of importance since by dropping the pieces into the tank in vertical position a uniform cooling is obtained. In this connection I may employ a tank having means by which the rate of cooling of the piece being treated can be accurately controlled. One form of such tank is shown 10 in Fig. 5. In this figure, 25 designates the tank proper, and 26 an inner compartment thereof having perforated lateral walls. This inner compartment may be made of any desired area in cross section 15 relative to the cross-sectional area of the piece being treated, and thereby (in the manner of a dash-pot) regulating the time required for the piece to become immersed therein. The cooling can be further regulated by the size of the perforations in the 20 wall of the compartment.

The tank 25 should be provided with a heavy bottom 27 sufficiently strong to stand the shocks when the pieces are dropped suddenly thereon.

The heating above described being also of a uniform character, very exact results in annealing and tempering of the metal can be obtained and these results can be accurately reproduced in successive pieces.

In some cases, however, it may be desired to slowly cool the treated metal while still under the action of the magnetic field. This can be readily effected by properly controlling the current in the heating coils. By employing an inner shell or lining 5 of a character to permit the circulation of induced currents therein, such shell or lining may be very quickly heated and may be 40 made to impart heat directly to the metal objects.

I preferably employ an alternating current of about sixty cycles for the production of the varying magnetic field, but do not 45 limit myself in this respect.

In Fig. 6 I have shown the apparatus arranged for the heating of water. In this figure the same numerals are employed to designate corresponding parts as in Fig. 1, 50 with the suffix *a*.

In this apparatus the metal pieces A and B are replaced by the liquid containers C and D, one of these containers having an inlet connection E, the other an outlet connection F, and the two containers having a bottom circulating connection G. In this form of my invention the action is the same as in the form first described, except that the material to be heated is a liquid within a 55 magnetic field. In this form of my invention it is not necessary that there shall be any automatic regulation of the current, although this can be readily accomplished by a thermostatic means of well known 60 character.

It will be obvious that in this manner, water, or other liquids may be heated, or various other heating operations may be carried out. The form of the apparatus may, of course, be varied to suit the particular object or materials being heated. Instead of being arranged to treat two pieces at once, the apparatus may be arranged to treat a single piece, or more than two pieces. The general construction and arrangement of the parts may be widely varied, the number of sections or units of the coils may be changed; other forms of current regulating switches may be employed, and various other changes may be made within the spirit and scope of the appended claims.

I claim:

1. Apparatus of the character described, comprising a hollow coil or winding adapted to inclose an article to be treated, said coil or winding being composed of a plurality of sections, a regulating switch to which said sections are connected, and means controlled by the flow of current through the sections for automatically operating said switch to connect the sections in different relations, substantially as described.

2. Apparatus of the character described, comprising a hollow coil or winding, means for supplying electric current thereto, and pieces of magnetic material adjacent to the ends of the coil or winding, the coil or winding being movable with respect to one of the end pieces, substantially as described.

3. Apparatus of the character described, comprising a hollow vertical coil or winding, pieces of magnetic material adjacent to the ends of said coil or winding, said coil or winding being movable toward and away from one of said pieces, substantially as described.

4. Apparatus of the character described, comprising a hollow coil or winding adapted to inclose a metal object to be subjected to the magnetic field thereof, and movable door means closing one end of said coil or winding, substantially as described.

5. Apparatus of the character described, comprising a plurality of hollow vertical coils or windings, each adapted to inclose a metal object to be subjected to the magnetic field of the coil or winding, and a casing of heat insulating material surrounding the same, substantially as described.

6. Apparatus of the character described, comprising a plurality of hollow vertical coils or windings, each adapted to inclose a metal object to be subjected to the magnetic field of the coil or winding, and a casing of heat insulating material surrounding the same, said casing and coils being movable together as a unit, substantially as described.

7. Apparatus of the character described,

comprising a hollow coil or winding adapted to inclose the object or substance to be heated, and switch means controlled by changes in the properties of such object or 5 substance for automatically controlling the current supplied to said coil, substantially as described.

8. Apparatus of the character described, comprising a hollow coil or winding, a 10 source of alternating current connected thereto, and means whereby changes in the properties of the material being treated are caused to automatically indicate when a predetermined heating temperature has been 15 reached, substantially as described.

9. Apparatus of the character described, comprising a coil or winding adapted to contain therein a piece of metal to be heated, a source of alternating current connected to said coil or winding, and means whereby changes in the magnetic properties of the metal being heated are caused to automatically control such supply of current, substantially as described. 20

In testimony whereof, I have hereunto set 25 my hand.

FREDERIC L. BISHOP.
